United States Patent Office

Des. 196,124
Patented Aug. 27, 1963

196,124

TOY FIGURE

Nicholas T. Argiro, 780 Riverside Drive,
New York, N.Y.

Filed May 3, 1961, Ser. No. 65,011

Term of patent 7 years

(Cl. D34—15)

FIG. 1

FIG. 1 is a perspective view of a toy figure showing my new design;

FIG. 2 is a side elevation;

FIG. 3 is a rear elevation; and

FIG. 4 is a horizontal section through FIGURE 2, looking upwardly in the direction of the arrows.

The broken line showing of dispensers is for illustrative purposes only.

I claim:

The ornamental design for a toy figure, as shown and described.
